UNITED STATES PATENT OFFICE.

CHARLES R. STEDMAN, OF CLEVELAND, OHIO.

SOUND INSULATION.

1,076,074.

Specification of Letters Patent. Patented Oct. 21, 1913.

Application filed June 10, 1912. Serial No. 702,918.

To all whom it may concern:

Be it known that I, CHARLES R. STEDMAN, a citizen of the United States, and a resident of Cleveland, in the county of Cuyahoga and State of Ohio, have invented certain Improvements in Sound Insulation, of which the following is a complete and full specification.

The purpose of my improvements is to afford simple and efficient means of insulation by the use of sheets or quilts of sound absorbent material as at present employed, but without injury to their sound deadening qualities by nailing through the sheets in order to bond the finish floor to the underlying structure.

Referring to the drawing Figure 1 shows a sectional view of ordinary floor construction in which my insulating system is employed, the surface lines being projected perspectively to better illustrate its application. Fig. 2 shows an enlarged scale section of parts included in Fig. 1.

The joists C and sub-floor B are the most common form of floor construction to which my method is applicable. Any other suitable under structure may be used or the sub-floor omitted. These members are hereafter referred to as the "supporting structure." Over this structure is laid insulating material A, usually in the form of sheets or quilts, and my invention pertains to the method of securing these sheets and the bearing strips D firmly in position without reducing the efficiency of the insulation by driving nails through it.

It will be noticed that the strips D are narrower at the top, one or both edges being beveled, as at O. The bond strips E are adapted to fit these edges, and the bearing strip D is thus dovetailed between the bond strips on either side. A strip of the insulating material A is placed between the parallel edges of the bond strip E and the bearing strips D which are then pressed closely together and the bond strips nailed down securely to the supporting structure. These nails M penetrate the main body of the insulation, but since the strips E through which they are driven are thinner than the bearing strips D to which the finish floor G is secured by nails L it follows that no contact exists between the finish floor G and the supporting structure except through sound-absorbent material. By methods heretofore in use the bearing strips are nailed

directly through the insulation into the supporting structure, in which case the nails afford direct transmission of vibrations between the finish floor and the supporting structure. Or, if laid without nailing, as is often the case, the flooring being tightly driven together tends to buckle, with the result that the finish floor and the strips to which it is nailed are often lifted entirely from the sub floor in parts of the room.

Continuing the improvement, I place a strip of insulating material A' under the base plate J of all partitions. The weight of the studding I nailed to this plate holds it down firmly, and it is prevented from lateral shifting by cleats K nailed to the supporting structure, a strip of insulating material also being interposed between these cleats and the plate J, and between the cleats and any adjacent bearing strips D Fig. 2.

Vibrations due to a blow on the partition are absorbed by the insulation instead of being, as heretofore, transmitted to apartments below.

In practice if the bond strips E are cut to a length equal to the distance between bearing strips they afford a convenient means of spacing the bearing strips, and if laid in courses distant from each other equal to the width of the sheets of insulating material it affords a means of securely binding the edges of the sheets.

Having described my improvements I claim as follows;

1. A system of sound insulation consisting of a quilt or layer of insulating material resting upon the supporting structure, bearing strips resting upon said quilt, said bearing strips being narrowest at the top, and bond strips adapted to fit the edges of said bearing strips and nailed to the supporting structure, a strip of insulating material being placed between said edges and said bond strips, and said bond strips being thinner than said bearing strips.

2. A system of sound insulation consisting of a quilt or layer of insulating material resting upon the supporting structure, bearing strips resting upon said quilt, said bearing strips being narrowest at the top, and bond strips adapted to fit the edges of said bearing strips and nailed to the supporting structure, a strip of insulating material being placed between said edges and said bond strips, and said bond strips being thinner

than said bearing strips, a layer of said insulating material being placed under the base of partitions, said base plate being held in place by cleats nailed to the supporting structure and separated from immediate contact with said base plate and any adjacent bearing strip by insulating material substantially as described.

3. The combination with a supporting structure of a quilt or layer of insulating material A, bearing strips D having beveled edges O, bond strips E adapted to secure

said bearing strips in a dovetailing manner, said bond strips and bearing strips being separated by insulating material and said bond strips being thinner than said bearing strips and nailed to the supporting structure, a finish floor resting upon and nailed to said bearing strips. 15

CHARLES R. STEDMAN.
